UNITED STATES PATENT OFFICE.

HUBERT A. MYERS, OF TOLEDO, OHIO.

WINDOW-CONTROL MEANS.

Application filed April 7, 1924. Serial No. 704,597.

To all whom it may concern:

Be it known that I, HUBERT A. MYERS, a citizen of the United States, and a resident of Toledo, in the county of Lucas and State of Ohio, have invented a new and useful Window-Control Means, which invention is fully set forth in the following specification.

My invention has for its object to provide an efficient window control mechanism for raising and lowering windows that is so constructed that it may be made at a low cost of production. The window control mechanism may be used for raising and lowering windows located in any structure, but the invention finds its greatest advantage when used for raising and lowering windows in vehicles, such as automobiles, since it is so constructed that the window may be raised or lowered by an actuating movement that is comparatively short in length and yet the window will be held locked as against any jarring that may be caused by the movement of the vehicle over the roadway. The window will thus maintain the position in which it is placed by the control member.

The invention may be contained in structures that vary in their form and to illustrate a practical application of the invention I have selected a structure containing the invention and shall describe it herein-after. The structure selected as an example is shown in the accompanying drawings.

Figure 1 of the drawings illustrates a side view of a part of the construction in which a window having a window control mechanism embodying my invention is located. Figure 2 illustrates a sectional view of the frame and shows an edge view of the window control mechanism. Figure 3 illustrates a flanged plate manually operated to raise and lower the window. Figure 4 illustrates a rack that is actuated by the plate shown in Figure 3. Figure 5 is a sectional view of a part of the rack shown in Fig. 4. Figure 6 is a sectional view of the cam plate and connected parts.

Constructions containing my invention are preferably so formed that they may be made of sheet metal whereby the parts may be made at a low cost by die cutting and pressing them to shape. In the construction shown in the drawings, an arm 1 that may be formed from sheet metal, is pivotally connected to a frame 2 that supports the

parts of the window control mechanism, and thus provides a means whereby the window control mechanism may be installed as a unit in the construction in which the window is located. The frame 2 is secured by suitable means to the structure in which the window 3 is located. The frame 2 may be connected to bars 4 forming a part of the skeleton or framework of the body of an automobile. The rotatable arm 1 and the frame 2 are preferably located in a pocket for receiving the window and into which the window may be lowered in the manner well known in the art. The arm 1 may be counter-balanced to a more or less extent by means of an involute spring 5, one end of which is connected to the arm 1 and the other end is connected to a fixed pivot pin used for pivotally supporting the arm 1. The outer end of the arm is provided with a roller 6 that rolls along the under side of the U-bar or channel bar 7. The channel bar 7 forms a protective covering for the lower edge of the glass 8 of the window. The U-bar 7 may be a part of a frame that extends, not only, along the lower edge of the glass 8, but also along two side edges. More commonly the channel bar 7 extends along the lower edge of the glass 8 only and covers the lower-edge portion of the glass. Thus the window 3 is supported on the roller 6 and as the arm 1 is swung on its pivot pin the window is raised or lowered according to the direction of the pivotal movements induced in the arm 1.

In order to prevent the roller 6 from slipping from beneath the edge of the glass, a pair of plates 9 and 10 are supported on each side of the roller 6 and on the pin 11 that pivotally supports the roller. The plate 9 may be in the form of a washer located on the pin 11. The plate 10 is located between the roller 6 and the end of the arm 1 and is provided with a lip 12 that hooks over a flange 13 that may be formed along the lower edge of the channel bar 7. As the roller 6 is moved along the lower side of the channel bar 7, the lip 12 will move along the flange 13 and so that when the resistance to the downward movement of the glass 8 is sufficient to overcome the weight of the glass, the arm 1 will positively draw the glass downward into the pocket. Also the lip 12 will prevent the glass from slipping from the roller on the

2 side of the roller on which the plate 10 is located. The glass 8 may be connected to the arm 1 by removal of the sill strip 14 and raising the roller to the top of the pocket 5 et. By placing the glass 8 in tilted position, the flange 13 may be slipped under the lip 12 and when the glass 8 is placed in vertical position it will be engaged thereby and between the plates 10 and 11. Thus 10 the glass 8 and the roller 6 will be maintained in position such that the glass 8 will be operated upon by the arm 1 whenever the arm 1 is actuated, and a rigid connection will be always maintained between the end 15 of the arm 1 and the window.

The arm 1 is actuated preferably by means of a crank operating through a simple and efficient mechanism that is so constructed that it will lock the arm 1 in any 20 position to which it may be moved, as against the weight of the window notwithstanding the jarring that may be produced by the movement of the vehicle over the road. The mechanical connection between 25 the crank 15 and the arm 1 comprises a cam plate 16 formed of sheet metal that may be easily cut and shaped by dies. The cam plate 16 is provided with a cam flange 17 that is involute in form, one end of the 30 flange 17 terminating at a point at substantially the same radial line that the other end is located on, and at a point somewhat greater from the center of rotation of the cam plate. The cam plate is connected to 35 the crank 15. The cam plate is located at a slight angle to the vertical sides of the frame 2 so as to bring the lower edge of the cam plate into engaging relation with a rack 18 and to permit the upper edge of 40 the cam plate to clear the teeth of the rack.

The rack 18 is also formed of sheet metal and consequently may be readily cut and pressed to shape by punch presses. It is so formed that it may be formed of a comparatively light weight metal and yet have the required strength to withstand any compression or tension that it is subjected to in the ordinary use of the mechanism. It is provided with teeth that may be struck up 45 from the sheet metal of which it is formed. In the construction shown in the drawing, the rack is provided with a plurality of pairs of teeth that are disposed in spaced relation to each other at distances apart that 50 are substantially equal to the distances between the ends of the flange 17 formed on the cam plate and so that in rotation of the cam plate the pairs of teeth will be engaged or disengaged by the end portions 55 of the flange 17 successively. The teeth of each pair are located sufficiently distant apart to permit the flange 17 to pass between the teeth of each pair and yet sufficiently close together to prevent free movement vertically of the rack 18 relative to 60 the flange 17. The teeth moreover have a curvature that corresponds substantially to the general curvature of the flange 17. The curvature of the flange 17 may change slightly and progressively from one end of 70 the flange to the other end, or the center of curvature may change to maintain a substantially constant curvature in the flange. The rack 18 may be formed of a pair of strips 19 and 20 that are bent in the form 75 of a channel. Tongues 21 and 22 are struck up from the web or bottom of the channels. The tongues 22 are inserted through the holes 23 that are formed in the channel 19 in cutting the channel 19 to form 80 and position the tongues 21. The tongues 21 and 22 are so positioned relative to each other that they will be located on opposite sides of the flange 17, as succeeding pairs of tongues are engaged in the succeeding 85 rotations of the cam plate. The channel members 19 and 20 may be secured in their relative positions by any suitable means. The channel 20 may be so formed as to fit within the channel 19 and the sides of the 90 channel 19 may have a width sufficient that they may be bent over the edges of the sides of the channel 20. Thus the channels 19 and 20 will be securely though frictionally connected to each other and securely held 95 in their relative positions.

The rack 18 is pivotally connected at one end to the arm 1 by means of the pivot pin 24, and is maintained in its operative relation to the cam plate 16 by means of a shell 100 25 which also constitutes a guide for the rack 18, as it is moved lengthwise by the operation of the cam plate 16. The shell 25 is pivotally connected to the shaft 26 while the cam plate 16 is provided with a hub 27 that 105 may be struck up from the plate, and is keyed to the shaft 26. The shaft 26 extends through the cam plate and an opening 28 formed in the shell 25. The outer end of the shaft 26 is riveted over the edge of the shell 110 about the opening 28 and so as to permit rotation of the shaft 26 relative to the shell 25 to produce rotative movements of the cam plate 16 relative to the shell 25. The rack 115 18 is thus moved through the shell 25 as the cam plate 16 is rotated, to engage successively the teeth of the rack. This swings the arm either upward or downward according to the direction of rotation of the cam plate, to raise or lower the window.

The shell 25 is preferably formed of sheet metal and may be easily cut and shaped by dies, it being provided with a box like portion 29 that fits around the sides of the rack 18. It also is provided with a channel portion 30 through which the teeth of the rack 120 freely pass. The ends of the sheet metal strip from which the shell 25 is formed overlap and are secured together by means of the riveting of the end of the shaft 26. The 125 130

sides of the channel like portion 30 are so formed as to maintain the plate 16 at a slight angle to the rack 18 in that the lower ends of the sides of the channel like portion 5 are shorter than the upper ends of the sides, which places the plate 16 and the shaft 26 at a slight angle to the vertical and horizontal respectively, and maintains the rack 18 in a vertical plane.

10 I claim:—

1. In a window control mechanism, a pivoted arm for raising and lowering the window, a rack pivotally connected to the arm, a flanged spiral cam for raising and lowering 15 the rack to raise and lower the window, a frame, a crank and shaft pivotally supported in the frame and connected to the cam for rotating the cam and a member swiveled on

the end of the shaft and located within the flange of the cam and surrounding the rack 20 for guiding the rack across the cam.

2. In a window control mechanism, a pivoted arm for raising and lowering the window, a rack pivotally connected to the arm, a flanged spiral cam for raising and lowering 25 the rack to raise and lower the window, a frame, a crank and shaft pivotally supported in the frame and connected to the cam for rotating the cam and an oblong member surrounding the rack and swiveled 30 on the end of the shaft and located within the flange of the cam for guiding the rack.

In testimony whereof, I have hereunto signed my name to this specification.

HUBERT A. MYERS.
